UNITED STATES PATENT OFFICE.

BERNARD F. STENZ, OF NEW YORK, N.Y.

PROCESS OF PRODUCING REPLICAS OF TEXTILE SAMPLES.

Application filed September 22, 1922. Serial No. 589,840.

The present invention relates to a process of producing replicas of textile samples, that is to say, replicas of the character disclosed in Letters Patent of the United States No. 1,047,849 dated December 17, 1912, granted to Simplex Lithograph Company on an application filed by me. In that patent is disclosed a textile sample card comprising a body portion struck up or embossed, so as to represent samples of textile material or piece goods, in such manner that the observer gets the impression that he is looking at an actual sample of textile fabric mounted upon a card. This effect is produced by so forming the struck up or embossed portions or panels, that they will have well defined marginal edges and a surface showing the weave, texture and pattern of the fabric, and also the color or colors of the fabric.

The object of the present invention is a simple process which can be quickly performed, for producing replicas of such textile samples, and one by which an accurate simulation of a piece of fabric can be produced.

Another object of this invention is a die for the rapid production of embossed cards accurately simulating the weave and thickness of a piece of textile fabric.

Further objects will appear from the following specification and the drawings.

The invention is illustrated in the accompanying drawings, in which—

Fig. 1 represents a blank from which the matrix is produced.

Fig. 2 shows a pattern of the sample card to be produced.

Fig. 3 shows the pattern shown in Fig. 2 laid upon the surface of the blank shown in Fig. 1.

Fig. 4 shows the pattern and the blank shown in Fig. 1 subjected to pressure sufficient to embed the textile samples of the pattern in the surface of the blank, and while the blank is being set or cured.

Fig. 5 shows the matrix with the recessed embossed panels thus produced.

Fig. 6 is a blank similar to Fig. 1.

Fig. 7 shows a cross section of the blank shown in Fig. 6, and the matrix shown in Fig. 5, the blank being laid upon the matrix.

Fig. 8 shows the blank and matrix subjected to pressure, so that the surface of the blank is forced into the recess of the matrix, and while the blank is being set or cured.

Fig. 9 shows the blank shown in Fig. 6, after it has been subjected to pressure and vulcanized, thus producing a male mold.

Fig. 10 illustrates the mold shown in Fig. 9, with the embossed surface covered with a metallic plating.

Fig. 11 shows the metallic plating thus produced stripped from the mold.

Fig. 12 shows the metallic plating backed up with lead or other metal, to form an embossing die.

Fig. 13 represents the embossing of a sample card by the use of such a die.

Similar reference characters will be employed to designate corresponding parts.

In carrying out my process I provide a blank 1, which of course may be of any suitable size and shape. It is made of yielding material, preferably one which will yield to receive surface impressions, and which thereafter may be cured or hardened, and for this purpose I preferably employ a blank of uncured or partially vulcanized rubber of substantially uniform thickness.

The pattern shown in Fig. 2 comprises a sample of textile material 2, of which a replica is to be produced in the embossed sample card, which is preferably adhesively affixed to a backing 3, which may be of cardboard, and as shown, there may be a plurality of the textile samples 2 arranged in regular order with relation to each other upon the backing 3.

The backing 3 is not absolutely essential, for it is obvious that the sample of textile material may be laid directly upon the blank 1, but the use of the backing adds to the convenience in handling the samples of textile material. Having secured the samples of cloth 2 upon the backing 3, it is laid face down upon the smooth surface of the blank 1, as indicated in Fig. 3. When thus assembled the parts are subjected to pressure between pressure plates *a* and *b* (see Fig. 4), by means of which the textile samples 2 will be embedded in the surface of the blank 1, and while thus held under pressure the blank 1 will be vulcanized or otherwise treated to harden or set or cure it to a greater or less degree, and for that purpose the pressure plates *a* and *b* may be ordinary heated pressure plates of any well-known vulcanizing press.

When the blank 1 has been sufficiently vulcanized the pressure is relieved and the pattern comprising the backing 3 and textile samples 2 stripped

therefrom, thus producing the matrix 4 (see Fig. 5). The matrix 4 by the steps just described, will be provided with recessed panels 5, the walls of which will be of a depth substantially equaling the thickness of the textile samples 2, with the bottom surface 6 of the recesses carrying an embossed replica of the texture, weave and pattern of the samples of textile fabric.

10 A blank 7 which may be of substantially the same character as the blank 1, or it may be made of wax, is now laid upon the matrix 4 covering the embossed recessed panels therein, as shown in Fig. 7, and 15 while thus positioned pressure is applied by the pressure plates *a* and *b* as shown in Fig. 8, forcing portions of the blank 7 into the recesses in the matrix 4, as clearly indicated in Fig. 8, and while thus held, the blank 7 20 if made of rubber will be vulcanized in the same manner as the matrix 4 was vulcanized, whereupon the parts are removed from between the pressure plates *a* and *b* and separated. The blank 7 will thus be provided 25 with the struck up panels 8, the edges of which will be substantially the thickness of a piece of textile fabric, and the surfaces carrying an embossed replica of the texture, weave and pattern of the samples of textile material. The mold member thus 30 produced as shown in Fig. 9, is by any suitable electro-plating process provided upon its upper surface with a thin metallic plating 9, preferably of copper, as shown in Fig. 35 10. This plating 9 is then stripped from the mold member 7, as indicated in Fig. 11, and provided with a metallic backing 10 which may be of lead or other suitable metal, as shown in Fig. 12, thus producing 40 an embossing die. This embossing die is then employed in embossing the cardboard 11, as indicated in Fig. 13, by an embossing roller 12 or other suitable pressure means, the product thus produced comprising 45 a single integral paper or cardboard sample card, having struck up on one surface thereof embossed replicas of the textile samples.

It is of course understood that in the 50 matrix shown in Fig. 5, the embossed surfaces are the exact reverse of those shown on the surfaces of the panels of the mold shown in Fig. 9, and that the finished die shown in Fig. 12 shows a reverse similitude of the 55 pattern shown in Fig. 2.

By employing unvulcanized rubber to 60 produce the matrix and mold it has been found that a much more perfect reproduction of the appearance of the woven textile fabric may be produced, for the reason that because of its elastic nature the pressure applied causes it to "flow," as it were, about each exposed thread, and to completely fill the interstices between the exposed threads, 65 and no matter how much pressure may be

applied the threads will not be flattened but retain their rounded shape, and thus the embossing die will have a substantially true representation of the surface conformation of the fabric. Aside from this advantage, the process is extremely simple and capable of being carried out in a short space of time, enabling a finished sample card to be produced in a much shorter space of time than by any other known process. 75

It will of course be understood that while I have shown and described the invention as employed in producing a sample card having several samples of textile material to be reproduced, and the use of a mount upon which the samples of textile material are affixed, the process may be employed to produce a sample card showing a single replica of a sample of textile fabric, and that the textile fabric may be laid directly upon the surface of the blank shown in Fig. 1 without a mount therefor, and of course the sample to be reproduced may be of any size or shape, not exceeding the surface dimensions of the blank shown in Fig. 1. 85

The gist of the present invention resides in the use of yielding blanks capable of receiving impressions and of being cured or vulcanized to set them to hold the impressions, and this material may be of rubber or any similar compound. 95

I claim:

1. The process of producing embossed replicas of textile samples which consists in embedding a sample of textile fabric in the 100 surface of an uncured blank of rubber, vulcanizing the said blank, removing the sample of textile fabric, applying to the first blank another blank, subjecting the blanks to pressure thus forcing the second blank into the recesses of the vulcanized blank, electro-plating the surface of the second blank, removing the plating from the surface and supplying a backing for the plating. 105

2. The method of producing replicas of a 110 textile sample which comprises embedding a sample of textile fabric in and substantially flush with the surface of an uncured rubber blank, retaining the sample in position while the blank is vulcanized, removing the sample, applying another uncured blank to the surface of the vulcanized blank, and subjecting the blanks to pressure to force a portion of the uncured blank into the recess in the vulcanized blank. 115

3. The method of producing replicas of a 120 textile sample which comprises embedding a sample of textile fabric in and substantially flush with the surface of an uncured rubber blank, retaining the sample in position while the blank is vulcanized, removing the sample, applying another uncured blank to the surface of the vulcanized blank, subjecting the blanks to pressure to force a portion of the uncured blank into the recess in the vul- 125

canized blank, and vulcanizing the uncured blank.

4. The method of producing replicas of a textile sample which comprises embedding a sample of textile fabric in and substantially flush with the surface of an uncured rubber blank, retaining the sample in position while the blank is vulcanized, removing the sample, applying a second uncured blank to the surface of the vulcanized blank, subjecting the blanks to pressure to force a portion of the second blank into the recess in the vulcanized blank, retaining the two blanks in juxtaposition while the second blank is vulcanized, separating the blanks, electroplating that surface of the second blank formerly in contact with the surface of the blank first vulcanized, and removing the plating from the surface of the second blank.
5. The method of producing replicas of a textile sample which comprises embedding a sample of textile fabric in and substantially flush with the surface of an uncured rubber blank, retaining the sample in position while the blank is vulcanized, removing the sample, applying a second uncured blank to the surface of the vulcanized blank, subjecting the blanks to pressure to force a portion of the second blank into the recess in the vulcanized blank, retaining the two blanks in juxtaposition while the second blank is vulcanized, separating the blanks, electroplating that surface of the second blank formerly in contact with the surface of the blank first vulcanized, stripping the plate from the surface of the second blank, filling the under side of the plate with a metallic backing, applying a sheet of paper to the outer side of the plate and retaining the plate and paper sheet in juxtaposition while subjecting them to pressure.

canized, separating the blanks, electroplating that surface of the second blank formerly in contact with the surface of the blank first vulcanized, removing the plating from the surface of the second blank, and filling the under side of the plating with a metallic backing.

6. The method of producing a replica of a textile sample which comprises embedding a sample of textile fabric in and substantially flush with the surface of an uncured rubber blank, retaining the sample in position while the blank is vulcanized, removing the sample, applying a second uncured blank to the surface of the vulcanized blank, subjecting the blanks to pressure to force a portion of the second blank into the recess in the vulcanized blank, retaining the two blanks in juxtaposition while the second blank is vulcanized, separating the blanks, electroplating that surface of the second blank formerly in contact with the surface of the blank first vulcanized, stripping the plate from the surface of the second blank, filling the under side of the plate with a metallic backing, applying a sheet of paper to the outer side of the plate and retaining the plate and paper sheet in juxtaposition while subjecting them to pressure.
